PLACARD

Antonino Alfano, Rome, Italy

Application September 21, 1932, Serial No. 634,248
In Italy September 21, 1931

1 Claim. (Cl. 41—34)

My invention relates to placards to be posted in a public place and reveals a new system for their production different from the typographical and lithographical proceeding hitherto used and 5 which cannot be considered as rational, neither from a technical nor an economical point of view.

Indeed the typographical technic is limited in its means created with the object of obtaining a great number of copies of small size and generally 10 of only three colours, and the lithography also is limited owing to the necessity of using a limestone for each colour and by the size of the stones. These two technics are of such common use and the fat and glossy appearance of the inks used 15 gives an effect of such ordinary nature, contrary to artistic sense, that the chief scope of placards—which is to attract the attention of the public—is not attained. Furthermore these systems require much time and therefore they are not adapted to 20 public advertising, as the placards must often be created and changed within a short time.

From an economical standpoint the two said systems become rational only for editions of some thousands of copies. But it is well known that 25 placards are required in a much minor number and often specially if the placards are of a very great size, they are reproduced in a few copies only, for which the reproduction by typographical or lithographical means is very irrational.

30 The placard and the system of producing it, according to the invention, have not these technical and economical disadvantages.

The invention consists essentially in superposing by layers and in fixing in any way (instead of 35 printing lithographing, painting etc.) on a support of any chosen materials, the one on the other and beside the other, the single graphical and colouristic elements of the subject and of the ground of the sketch, that is to say of the whole 40 project, cut or taken from strips, sheets and the like varying in substance or colour, composing in such a way a reproduction in relief.

The invention is illustrated in the accompanying 45 drawing, in which:

Figure 1 is a view of the original sketch.

Figure 2 is a view of an enlargement of the sketch.

Figure 3 shows the various patterns made by 50 dividing the enlargement to produce the several parts indicated.

Figure 4 is a perspective view illustrating the application of one of the patterns on a pile of superimposed sheets to permit simultaneous cutting of all of the sheets in accordance with the 55 pattern.

Figure 5 shows the superimposed sheets cut in accordance with the pattern, it being understood that each of the separate parts shown in Figure 3 serve as patterns for cutting the sheets.

Figure 6 shows the completed placard made up by securing thereon the form resulting from the use of the patterns in cutting the sheets to provide a placard or several such placards in exact accordance with the original sketch, differing therefrom only as to size or color or material as 10 may be indicated.

A small sketch 1 of the placard to be reproduced is enlarged as at 2 by means of a projecting apparatus to the size of the placard desired. From this enlargement the shapes for the back-ground, 15 the single letters and the elements 3 composing the placard and having the same colour are made with cardboard, sheet-metal and other material and these forms 4 are each placed on a small pile of sheets 5, strips, sheet-metal of material and 20 colour corresponding to the same effect which this element produces in the project, tracing for example, the edges of the said forms with a knife or with scissors and cutting at one time the whole pile which is composed of the number of sheets 25 allowed by the kind of material used (for example ten sheets of paper at one time), and producing in such a way the required number of each element indicated at 6, pasting or fixing in any way 30 these elements on a support as indicated at 7, for example cardboard, the one on the other or beside the other, according to the effect or the relieve one wishes to produce. If the placards to be 35 posted on the wall or on boards are of very large size they are opportunely subdivided in more sheets, choosing as a support not cardboard but paper or cloth and composing the single sheets on the place of application. It will be understood that the single piles of sheets 5 on which the 40 shape of each element is put can be composed by sheets of different colour and in this way it is possible to change the colours from one placard to the other, without more cost or labour.

The advantages of the proceedings, according 45 to the invention, consist in the greater clearness of the separating lines between the various elements placed the one on the other, clearness due to the fact that the lines are cut out by a blade,—in the more pronounced contrasts, due to the difference between the materials used, such as 50 cloth and paper of mat surface (an effect not obtainable by printing) besides materials of a glossy surface,—in the amazing effects of combination between metallized paper, sprinkled paper, velvet paper, photography, phosphorescent materials 55

etc.—in the new relieveo effects,—in the possibility of varying the colours and the effects from one placard to the other without incurring extra expense or labour,—in the possibility of producing 5 economically even one single placard,—in the possibility of combining twenty and even more different colours or effects.

What I claim is:

A method of producing placard reproductions, 10 consisting in making a sketch of the placard to be reproduced, enlarging the sketch to the size of

the desired reproduction, dividing the enlargement into its elements of equal color and light effect, forming patterns corresponding to the shapes of the elements as divided, superimposing the patterns on a pile of sheets of materials of different colors and effects, cutting the sheets in accordance with the pattern in a single operation, and fixing the cutouts on a support in correspondence with the arrangement of the similar elements in the sketch. 5
